UNITED STATES PATENT OFFICE.

MELVILLE E. DAYTON, OF CHICAGO, ILLINOIS.

AIR-PRESSURE APPARATUS FOR VAPOR-STOVES AND OTHER PURPOSES.

SPECIFICATION forming part of Letters Patent No. 363,610, dated May 24, 1887.

Application filed September 21, 1885. Serial No. 177,637. (No model.)

To all whom it may concern:

Be it known that I, MELVILLE E. DAYTON, of Chicago, in the county of Cook and State of Illinois, have invented certain new and useful

5 Improvements in Air-Pressure Apparatus for Vapor-Stoves and other Purposes; and I do hereby declare that the following is a full, clear, and exact description thereof, reference being had to the accompanying drawings, and to the 10 letters of reference marked thereon, which form a part of this specification.

Generally stated, this invention relates, primarily, to contractile air-chambers for vapor-stoves and similar purposes, which air-chambers are intended to be subject to a continuously-acting weight or equivalent force, and are therefore adapted to serve in producing a continuous and uniform pressure upon the liquid to be expelled from the liquid tank 20 or reservoir. More particularly stated, it relates, primarily, to that class of contractile air-chambers of the plunger order, which comprise telescoping cylinders as the means whereby an inclosed air-space is contracted and the 25 air is forced therefrom into the liquid-tank, whence the liquid or vapor is sought to be expelled.

Among the objects of this invention are, first, that of providing an improved construction in this class of contractile air-chambers, and, second, that of providing a compact and desirable arrangement of the contractile air-chamber with the liquid-tank of a hydrocarbon-vapor stove or analogous apparatus.

30 35 To these and other ends, that will more fully appear, the invention consists in the matters hereinafter set forth, and pointed out in the appended claims, it being understood that my invention is not restricted to the precise details of construction shown in that form of my invention which I have herein illustrated as what I now believe to be the best form in which it can be embodied.

In the accompanying drawings, Figure 1 is 45 a side elevation of a contractile air-chamber containing my improvement applied to a hydrocarbon-vapor stove, in which the hydrocarbon-liquid tank is separate from the air-chamber. Fig. 2 is a central vertical section 50 of the contractile air-chamber shown in Fig. 1. Fig. 3 is a perspective view detached of the rolling ring which is placed between the

telescoping cylinders of the air-pressure mechanism. Fig. 4 shows a straight piece of which the ring is preferably made. Fig. 5 is an elevation of the combined liquid-tank and contractile air chamber or air-pressure mechanism applied to a vapor-stove, the view being from the rear of the stove. Fig. 6 is a top view of the combined liquid-tank and air-pressure mechanism shown in Fig. 5. Fig. 7 is a central vertical section of the combined liquid-tank and air-pressure mechanism in the line *xx* of Fig. 6. Fig. 8 is a detail section enlarged from Fig. 7. Fig. 9 is a plan or top view of the matters shown in Fig. 8. Fig. 10 is a detail construction which may with advantage be employed instead of that shown in Figs. 8 and 9. Fig. 11 is a detail shown in vertical section of the top plate through *yy* of Fig. 6.

A is the frame of a vapor-stove.

B is a hydrocarbon-liquid tank. At C C are vapor-burners, which are all here represented as of the self-generating order.

D is a pipe leading from the bottom or near the bottom of the liquid-tank B, either directly or through a branch or branches, D', to the generating-chamber of the burner or burners C.

Coming to the part with which my invention is more directly concerned, E is an open-topped hollow cylinder communicating by a pipe or passage with the liquid-tank B. F is a smaller and weighted cylinder, fitted to enter the cylinder E and to afford a space, *e*, between them.

G is a rolling ring, which occupies the space *e*, and forms a stop to the escape of air from the space beneath it embraced by the cylinders, 90 except by the passage provided therefor which leads to the liquid-tank. The ring G is necessarily of soft or compressible material, and is preferably made of rubber, either tubular or solid, in order that it may not slip or 95 slide upon the dry and practically smooth surface of either of the cylinders with which it is in contact, but may, on the other hand, adhere to said surfaces, and be thereby caused to roll as the weighted cylinder descends or is raised. 100 When free, said ring G is sectionally cylindric, and is somewhat thicker than the width of the space *e*, so that when in place between the cylinders it is compressed into ovoid sectional

form, and exerts a resilient force upon the surfaces of the cylinders E and F, productive of sufficient friction to prevent its displacement by the pressure of air beneath it, and to insure the rolling effect referred to.

The rolling ring G is conveniently put in place by placing it over the lower end of the cylinder F, and then forcing both into the upper end of the larger cylinder, E. Thus inserted, it is evident that the ring cannot descend more than half the length of the cylinder E, because when it has reached this point the inner cylinder will have reached the limit of its descent. Accordingly, the pipe or passage leading from the air-chamber to the air-space of the liquid-tank may be taken off either at the bottom or at any other point below the middle of the cylinder E, as well as through the plunger, and thence by a flexible tube to the top of the liquid-tank.

H is a removable ring inserted in or otherwise applied to the upper end of the cylinder E. It forms, essentially, an inwardly-directed flange about the top of said cylinder when continuous, and serves in this form both as a guide by which the weighted cylinder F will be kept vertical as it descends and also as a guard to exclude anything that might otherwise fall into the space e. Two parallel rings, G, will also obviously operate to keep the weighted cylinder substantially upright.

In Figs. 1 and 2 the liquid-tank B is a structure wholly separate from the air-pressure device described, and is connected therewith by an exposed pipe, I, leading from the bottom of the air-chamber.

In Fig. 7 the liquid-tank B is shown as surrounding the cylinder E and as communicating with the air-space within the latter by a side passage, e', and pipe I.

In the combined liquid-tank and air-chamber shown in Fig. 7, (a fragment of the cap of which is shown in Fig. 8,) I prefer to employ an annular cast-metal top plate, J, as a means of tightly closing the top of the liquid-tank thus formed between the cylinders E and b, and in this casting to provide the necessary inlet-opening and threaded passages for the pipe or pipes which lead to the burner or burners.

J' is a screw-threaded opening, through which the liquid is supplied to the tank, and is desirably formed in a depending boss in order that the tank may not be conveniently filled quite to the top.

The air-pipe I is shown in Figs. 7 and 8 as in open communication at its top with the interior of the liquid-tank, and as rising above the bottom of the boss J', which will ordinarily be the highest level of the liquid in said tank; but in order to more certainly prevent the passage of liquid into the pipe I under any circumstances I have also in the construction shown in said Figs. 7 and 8 provided for the extension of the pipe I above the level of the overflow-point j at the inlet. This is done by forming a short vertical tube or re-

cess, J², in the top plate, J, somewhat larger 70
interiorly than the pipe I, and within which
said pipe I terminates at the required height
with respect to said overflow-point j and
below the top of the tube J². The air expelled
from the air-chamber through the tube I finds
free ingress to the space above the liquid in
the tank B over and about the top of said
pipe. I' is a valve, shown as consisting of a flat
disk of metal or leather fitted loosely within
the tube J² and resting (when the apparatus
is not in action) on the top of the pipe I.
This valve serves to close the pipe I wholly
or sufficiently when the air-chamber is being
recharged, and to keep up the pressure of air
in the liquid-tank B during such brief opera- 80
tion of recharging. To keep the pipe I in
place centrally within the tube J², a notched
or serrated disk, I², may be attached to the
tube or to the pipe at a point within the tube.
If this form of check-valve is employed, it
may, if preferred, be provided with a light
shank, I³, of wire, depending within the tube 90
to assist in keeping the valve horizontal and
in place. Such a valve and depending shank
applied to the open top of a pipe is not new
with me. The top of the tube J² is closed by
a cap, J³, which is preferably a disk of tin
soldered in place, instead of being screwed on
the tube, because there is never a need for re- 95
moving it, except the valve shall become de-
ranged. This cap may, as shown, form a stop
limiting the upward movement of the valve
under sudden or extreme pressure in the air- 100
chamber, and preventing its getting out of
working position.

In Fig. 10 the tube J² is made double or with two holes, j' j'', leading downwardly from 105
a common chamber, recess, or passage, j', over
which the cap J³ is placed. In one of these
holes, as j', the upper end of the pipe I is
tightly fitted or packed, and the valve I', or any
other desired form of valve, is applied to the 110
open top of the pipe I, as previously de-
scribed. The air which rises through the pipe
I into the chamber or recess j'' passes thence
down into the liquid-tank through the other
hole, j''. If necessary or desirable to the car- 115
bureting of the air, the pipe I' may be in-
serted in the hole j'' and lead to a point near
the bottom of the liquid-tank. The air will
thus be forced through a body of liquid hy- 120
drocarbon before entering the air-space at the
top of the liquid-tank, and will thereby be
carbureted to the desired point of inflamm-
ability. The bottom of the recess j'' is desir- 125
ably above the level of the overflow-point j,
for the same reason stated concerning the pipe
I in Figs. 7 and 8.

In Figs. 5, 6, and 11 two pipes are shown as leading from the liquid-tank—one, D, for the conveyance of liquid to the generator or burner, and a second pipe, D², for carbureted 130
air to be used (if at all) in initially heating the
generator or generators by auxiliary "burn-
ers" C' C. Both these pipes, as shown in
said Figs. 5, 6, and 11, may pass through a

boss or bosses, J^4 , on the cap-plate J , the former leading to a point near the bottom of the tank B , and the latter terminating at the top of said tank, as shown in Fig. 5. 5 K is a valved pipe, giving air-passage through the cylinder or plunger F , to enable the air-chamber to be recharged from time to time. L is a handle at the upper end of this tube, by which the weighted plunger may be conveniently lifted. 10 This handle is preferably contrived to open and close a valve applied to the pipe K by a rotative movement of the handle on a vertical axis, so that the valve may be opened preparatory to raising the plunger, the plunger may then be raised, and finally 15 may be held up while the valve is closed, all with one hand. As one suitable construction for this purpose, M , Fig. 7, is a conical valve-plug having a threaded shank, m , which enters the pipe-coupling K' . The plug M has a vertical recess, m' , continuous with the passage of the pipe K , and also a lateral passage, m^2 , leading from said recess m' . The handle L in this construction is provided with a sleeve, 20 L' , which is ground to fit the plug M , and which is provided with a lateral passage, n , properly located to allow of its being brought into coincidence with the passage m^2 . A packing-ring or gasket, n' , is desirably inserted between 25 the sleeve L' and the coupling K' , and a square projection, m^3 , on the top of the plug enables the latter to be run down tight. The operation of this form of handle-valve is obvious. When it is desired to lift the plunger, the handle will be seized and first turned to bring the 30 passages n and m^2 into coincidence with each other. The plunger is then lifted, and while the hand still upholds the plunger, it turns the handle back into position to close the passage m^3 , whereupon the handle is released. 40 A suitable stop is shown at m^4 , to limit the rotative throw of the sleeve L' on the plug M .

In Figs. 1 and 2 an ordinary plug-valve is shown independent of the handle L , and which 45 will be required to be closed by one hand, while the plunger is upheld by the other.

For use in connection with a vapor-stove the flame of which is extremely sensitive to variation in pressure and requires to be as 50 steady as possible, I prefer to make the rolling ring G with the same quantity of material upon one side as upon the other, though it will of course be compressed on whichever side happens for the time being to be the inner side 55 and expanded on the outer side. This may be done in one way by making the ring of an originally straight piece of rubber cylinder and giving it the continuous or angular form by bringing together and uniting the ends 60 thereof. Thus constructed, the ring has no pronounced tendency to turn into one position, as to some extent true in the case of a ring originally molded in annular form, and it opposes the rolling movement required of 65 it about equally at all points in the descent of the movable cylinder.

In a domestic vapor-stove I have found that

a ring, G , of rubber one-fourth of an inch in thickness, working in a space, e , only slightly less in width, say three-sixteenths of an inch wide, and upon the dry and practically smooth surfaces of the cylinders, operates with perfect success. 70

As represented in the drawings, a considerable constant weight is provided in the cylinder or plunger E . It is not material how this is applied. In Fig. 2 it is shown as consisting of a body of sand within the plunger, and in Fig. 7 it consists of a hollow casting surrounded by the sheet-metal cylinder F , which 75 gives the desired smoothness of surface without the cost of turning off the castings. 80

P are subsidiary and removable iron weights, slotted inward from one side to fit around the pipe K like scale-weights. These 85 may be used temporarily when a greater than usual or minimum pressure of air is required on the liquid-tank.

I am acquainted with the matters set forth in Letters Patent No. 347,161, granted August 10, 1886, to Samuel Daniels. I am also aware that it has been proposed to employ in a water-pump a rolling rubber ring between two circumferentially-corrugated cylinders, the corrugations on the cylinders being for the purpose 95 of preventing the ring from slipping upon the wet surfaces of said cylinders. This is not my invention. 90

I desire it to be understood that such modifications of the devices described and pointed out in the claims as shall attain one or more, but less than all, of the advantages or results herein set forth are not to be therefore regarded as a departure from my invention. 100

I claim as my invention— 105

1. The combination, with a tank or reservoir from which a liquid is to be expelled, of a contractible air-chamber communicating with the tank, and comprising two telescopic cylinders having a space between them, and having dry and practically smooth adjacent surfaces, a yielding ring in said space, which ring is normally cylindric and thicker than the width of said space, said ring being adapted to adhere to the dry smooth surfaces 110 of the cylinders when compressed between them, and a weight applied to the movable cylinder, substantially as described. 115

2. The combination, with two telescoping cylinders having a space between them, one 120 of said cylinders being movable, of a rolling ring of yielding material occupying said space, which ring is normally cylindric in section and thicker than the width of said space, and which in its annular form has its material 125 compressed on its inner side and expanded on its outer side, whereby it opposes a more uniform resistance to the movement of the movable cylinder, substantially as described.

3. The combination, with two closed and 130 telescoping cylinders having a space between them occupied by a rolling ring, one of said cylinders being weighted and the whole forming an automatically-contractible air-chamber

having inlet and outlet passages, of a guide which preserves substantial coincidence of the axes of the two cylinders, substantially as described.

5. The combination, with the two closed and telescoping cylinders having a space between them occupied by a rolling ring, one of said cylinders being weighted, and the whole forming an automatically-contractible air-chamber having inlet and outlet passages, of a guide on one of the cylinders which proximates the other cylinder, substantially as described.

15. The combination, with the burner or burners and the liquid tank of a hydrocarbon-vapor stove, of an automatic air-pressure chamber having a valved air inlet and an outlet communicating with said liquid-tank, said air-chamber being composed of two upright closed telescoping cylinders having a space between them occupied by a laterally-compressed sectionally cylindric ring of rubber or similar material, adapted to adhere to the dry surfaces of the cylinders, and the movable one of said cylinders being weighted, whereby the air is 20 expelled from the chamber to the liquid-tank by a constant force acting uniformly and producing a steady flame at the burners, substantially as described.

25. The combination, with the stationary and movable parts of a contractible air-chamber having an outlet-passage, of an air-inlet passage through the movable part, provided with a valve which is rotatable on a vertical axis, and a lifting-handle connected with said valve, whereby the same hand which lifts the movable part of the air-chamber may open and close the valve by lateral rotation of the hand, substantially as set forth.

7. The combination, with an air-chamber, means for pressing the air therefrom, and a liquid-chamber communicating with the air-chamber, of a top plate on the liquid-chamber, provided with a filling-orifice, and also provided with a recess opening into the interior of the liquid-chamber, and an air-pipe leading 45 from the air-chamber and terminating in said recess above the level of the lower end of the filling-orifice, substantially as described.

8. The combination, with an air-chamber, means for pressing the air therefrom, and a liquid-chamber communicating with the air-chamber, of a top plate on the liquid-chamber, provided with a filling-orifice, and also provided with a recess which opens into the interior of the liquid-chamber, and an air-pipe 55 leading from the air-chamber and terminating in said recess above the level of the overflow-point of the filling-orifice, substantially as described.

9. The combination, with a liquid-tank having a top plate provided with a recess having a downwardly-directed opening, of an induction air-pipe which opens upwardly into said recess, an automatic check-valve applied to the upper end of said air-pipe, and an externally accessible and removable cap which closes the top of said recess, substantially as described.

In testimony that I claim the foregoing as my invention I affix my signature in presence of two witnesses.

MELVILLE E. DAYTON.
